UNITED STATES PATENT OFFICE.

KENNETH IRWIN CROSSLEY, OF MANCHESTER, AND WILFRED LE PLASTRIER WEBB,
OF HALE, ENGLAND.

INTERNAL-COMBUSTION ENGINE.

1,410,894.

Specification of Letters Patent. Patented Mar. 28, 1922.

Application filed July 22, 1916. Serial No. 110,667.

To all whom it may concern:

Be it known that we, KENNETH IRWIN CROSSLEY and WILFRED LE PLASTRIER WEBB, both subjects of the King of Great Britain, 5 residing, the former at Crossley Brothers Limited, of Openshaw, Manchester, in the county of Lancaster, England, and the latter at Rostrevor, Hale, in the county of Chester, England, have invented new and useful 10 Improvements in Internal-Combustion Engines, of which the following is a specification.

Our invention relates to the kind of internal combustion engine which uses the 15 heavier fuel oils and in which the oil is injected by itself as spray (without the aid of injection air) into the compressed and therefore heated air in the combustion chamber towards the end of the compression 20 stroke, the air being compressed and therefore heated to such a degree that when the oil is sprayed into the combustion chamber it is ignited.

We are aware that engines of the kind described have previously been started from the cold state by compressing the air usually to about four hundred and fifty pounds, although compression pressures as low as about two hundred and fifty to three hundred pounds per square inch above atmospheric pressure have been proposed, but in order to enable such engines to be started from the cold state, and to vaporize and ignite their oil charges without the aid of externally applied heat, the oil just behind the spraying orifice or orifices has, we believe, during the period in which it is sprayed into the combustion chamber, been subjected to extreme pressure, i. e. about two thousand to 40 six thousand pounds per square inch, so that by the large and sudden drop or pressure between the two sides of the spraying orifice or orifices, together with the heat of the compressed air into which the injection takes place, the finely atomized oil spray is instantly vaporized and ignited. These extreme pressures of oil injection have been hitherto found necessary.

Our invention is based on the appreciation that (1) these high pressures of oil injection have been required because when oil is injected by itself as spray into heated air for combustion, instantaneous vaporization and mixing with the air are difficult to

attain and (2) by providing for a prolonged 55 contact of the spray with the heated air, prolonged either in time or distance or both, vaporization and mixing can be greatly facilitated and the certainty of ignition improved.

It is to be noted that when spray issues from an atomizing orifice, the greater the contact with the air the better are both the vaporization and the mixing. Greater contact may arise from a lower velocity of efflux of the spray over a longer period of time (giving a slower travel) or from the provision of a longer path of travel, or both.

Our invention consists of improvements by means of which we are able to start an 70 engine of this kind from the cold state, and vaporize and ignite its charges without using a lamp, or any form of heat supply except that produced by the work done in compressing the air in the cylinder or combustion chamber, whilst using lower oil injection pressures and in some cases with lower compression pressures.

In our invention we inject the oil spray into the combustion chamber at a pressure 80 immediately behind the spraying orifice or orifices of only about one thousand pounds per square inch or even in some cases considerably less. The oil spray may be somewhat coarser but there is no objection to this 85 as we depend upon the relatively prolonged contact of the oil spray or vapour with the compression-heated air in a combustion chamber of specially chosen shape for the efficient vaporizing of the oil spray for its 90 mixing with the air and for the resulting certainty of ignition of the mixture.

We construct the combustion chamber in such a manner and of such a shape as to present approximately as small a wall surface as possible for containing the air at the end of the compression stroke. This entails a rounded or approximately spheroidal shape, a part of the end of the piston and any valve or valves required forming portions of the containing walls. This construction ensures that the oil spray or vapour travels through a considerable distance on its path towards the core of the compressed and thereby heated air in the combustion 105 chamber, it also ensures that the said core is cooled as little as possible by the influence of the lower temperature of the containing

- walls. The shape which gives the least surface in proportion to the contained volume is of course a true sphere; but, as vaporizing of the oil spray is effected by and in the air
- 5 in the combustion chamber, it follows that the temperature of the air in the neighbourhood of the entering oil spray will be somewhat lowered and that if the combustion chamber is approximately spherical, the hot-
10 test zone in the combustion chamber, at the instant immediately previous to ignition is somewhat away from the centre of the sphere in the direction opposite to the point where the sprayer is located. As this may tend to
15 make the hottest zone or core of the air unduly near, and be adversely affected by the cold walls on that side of the combustion chamber, we prefer to somewhat counteract this effect by elongating the combustion
20 chamber so that it is of such convenient form or shape as will allow its length in the direction in which the oil is sprayed to be not less and preferably greater than either of its other two dimensions as, for instance,
25 prolate spheroidal or oviform or modifications thereof, all of which forms including an approximate sphere are herein conveniently referred to as "approximately spheroidal."
30 The combustion chamber is provided with a water jacket, except in such places where any air admission valve or exhaust valve or starting valve or oil sprayer or cleaning door is placed, and which is not usually water
35 jacketed.
- The oil being injected at lower pressures than is usual in engines of the kind described, a simpler and cheaper oil pump and operating gear and oil sprayer can be used,
40 and the very small spraying orifice may be larger in size or if several such orifices be used they may be larger in size or less in number and consequently more easily made and less liable to obstruction. Also as with
45 our invention we can start engines from the cold state when the compression pressure is less than three hundred pounds per square inch above atmosphere there is a further advantage that a lower initial pressure may be ensured when the charge is ignited and consequently the engine may be made both lighter and cheaper.
- In some cases, we prefer to reduce the size of the inner end of the engine piston
50 and to arrange for this reduced portion of the piston to enter the combustion chamber, so that by an increase of turbulence the vaporizing of the oil spray and the mixing of the oil spray or vapour with the air is im-
60 proved; air towards the end of the compression stroke being displaced suddenly from the cylinder into the combustion chamber through the space between the reduced end of the piston and the entrance to the com-
65 bustion chamber.

Referring now to the accompanying diagrammatic drawings which illustrate certain examples of construction according to our invention:—

Figure 1 illustrates in sectional elevation, 70 an example of an elongated and approximately oviform shape of combustion chamber with the fuel oil arranged to be sprayed from its smaller end (as indicated by the dotted lines spreading out from the sprayer) 75 in a mean direction corresponding approximately to the major axis of the chamber.

Figure 2 is a cross section of the same, and shows how in this example the chamber is somewhat flattened in shape. It will be readily understood that just before the piston reaches the end of the compression stroke when the oil spray is being injected, the shape of the chamber in cross section is less flattened and more nearly circular. 80

Figure 3 illustrates another example of oviform combustion chamber arranged so as not to give the turbulence effect indicated above.

Figure 4 is a sectional elevation illustrating similar parts of the usual type of cold starting heavy oil engine, and in which the oil spray is injected either with or without the aid of highly compressed air. 90

The oil sprayer valve is indicated at SV, 95 the spraying orifice at O, the oil chamber behind the spraying orifice at OC, the combustion chamber at C, the piston at P, and the reduced portion of the end of the piston (when used) at T. Any valve used is arranged with its head to form part of the walls of the chamber, as shown for example at V. The hottest core or zone during spraying is indicated approximately by the space contained within the dotted lines at H. 100

The same letters indicate similar parts in the different figures.

The elongated and somewhat oviform shape of combustion chamber, as shown in Fig. 1, tends to prevent the hottest zone or 110 core in the combustion chamber (which would under more ordinary circumstances be at or near the mean centre of the chamber) being so adversely affected by the cooling action of the entering oil spray as for it 115 (the hottest zone) to be moved unduly near and be unduly affected by the cooling influence of the cold walls enclosing the end of the chamber opposite to the oil sprayer, as this might thus tend to lower the temperature of the hottest zone to such an extent as to be insufficient to effect ignition satisfactorily. (It will be understood that if ignition is sluggish, the combustion will not be prompt and efficient). With such an elongated form of combustion chamber the hot- 120 test zone or core is not moved unduly near the cold walls opposite to the sprayer, but only to a position such say as H, which lies at a substantial distance from various parts 125 130

of the walls of the chamber. With this somewhat elongated form of combustion chamber, the temperature of the air in the hottest zone towards the end of the compression stroke is higher than it otherwise would be, the vaporizing of the oil spray and the mixing of the oil spray and vapour with the air between the sprayer and the hottest zone is more efficient on account of 10 its longer path through dense hot air, the depth of the hottest zone H is greater, and consequently a greater margin of certainty of ignition is secured. With this arrangement a lower compression pressure and temperature can be used than would be necessary with a less favourable shape of combustion chamber.

When the engine is being started from the cold state, according to our invention, oil is 20 delivered by any suitable means to the orifice or orifices of the oil sprayer at a pressure of about one thousand pounds per square inch or even considerably less, and at the desired moment immediately begins to issue as 25 spray from the very small orifice or orifices of the sprayer, the spray being then efficiently vaporized during its passage for a substantial distance through hot compressed air towards the hottest zone in the combustion chamber (such as for example at H), and is then ignited by the temperature of 30 the air at or near such hottest zone, and we wish it to be clearly understood that no source of heat is used for the purpose of 35 ignition, except that produced by the work done in compressing air in the engine cylinder and combustion chamber.

In Fig. 4 we have shown the usual shape of combustion chamber employed in cold 40 starting heavy oil engines, and it is readily seen that the hottest zone or core in this case is very flattened in shape, being somewhat as indicated at H. It is necessarily affected by the close proximity of the cold walls of 45 the piston and combustion chamber, and also by the oil spray, so that the vaporizing and ignition time is extremely short. Unless therefore the oil, on being injected, is instantaneously vaporized as it issues, it will 50 fail to ignite or burn satisfactorily. It is for this reason that it has been considered necessary hitherto to subject the oil to pressures of from two thousand to six thousand 55 pounds per square inch immediately behind the spraying orifice or orifices in order to ensure starting. Even with such pressures, owing to the unfavourable conditions just indicated, some of the oil at starting is liable to be deposited on the piston head, either 60 due to the vaporization being only partial, or owing to re-condensation taking place, with the result that ignition is sluggish or precarious, and starting unsatisfactory. This is especially the case when it is sought 65 to use less than 450 pounds per square inch

compression pressure in usual engine constructions.

On the other hand, when using approximately spheroidal shapes such as an approximately spherical combustion chamber, 70 we can with our invention, start the engine from the cold state, and satisfactorily vaporize, ignite and burn the oil charges with low compression pressures say about three hundred and fifty pounds per square inch, or, 75 if an elongated combustion chamber is used, as we prefer, for instance oviform as illustrated in Fig. 1, we can start the engine from the cold state and satisfactorily vaporize, ignite and burn the oil charges when 80 using a compression pressure even as low as two hundred and fifty pounds per square inch.

As an example, an oil engine which we have constructed and which we can start 85 from the cold state, according to our invention, has a piston fourteen inches in diameter with a stroke of twenty-three inches, an elongated combustion chamber approximately oviform in shape, and a compression 90 pressure of about two hundred and eighty pounds per square inch. This engine can be started by first admitting from a storage receiver to the engine cylinder and expanding therein a few charges of compressed air 95 in the well known manner and at a pressure of about two hundred to two hundred and fifty pounds per square inch, and in a few cycles the heat due to the work done in compressing the air in the cylinder during 100 the compression stroke will ignite the heavier oil spray charges of say Russian crude oil (having a viscosity of about seventy seconds at seventy degrees Fahrenheit, as determined in the Redwood viscometer), 105 when injected into the combustion chamber towards the end of the compression strokes of the engine piston through four small orifices having a total combined cross sectional area of one-seventeen-hundredth of 110 a square inch, at a pressure immediately behind the spraying orifices of about one thousand pounds per square inch, the engine then continuing to work under its own power and vaporize, ignite and burn its 115 charges satisfactorily.

With oils having higher flash points, higher air compression pressures may be used to obtain the higher temperatures required. Further, the oil injection pressures 120 required to obtain the same atomization, vary with the degree of viscosity of the oils, but we find it is not necessary to use oil injection pressures appreciably exceeding one thousand pounds per square inch.

In Figs. 1 and 2 we have shown the combustion chamber and piston arranged for turbulence utilization, which we sometimes prefer, the end of the piston being reduced in diameter at T, and projecting into the 130

entrance to the combustion chamber towards the end of the stroke, and then displacing the air from the space around the reduced end of the piston into the combustion chamber through the clearance space between the end of the piston and the entrance to the chamber, and causing considerable turbulence therein. This turbulence is arranged so as not to unduly affect the hottest zone 10 or core H, but to tend more towards scouring the walls.

Although we, in some cases prefer the utilization of considerable turbulence as indicated, it is not a necessity, and the piston 15 and the combustion chamber may be suitably arranged so that no such considerable turbulence takes place, either by omitting the part T, or as shown in Fig. 4.

In the forms illustrated, the direction of 20 spraying and major axis of an elongated chamber, when used, are disposed at right angles to the axis of the cylinder. It is, however, to be understood that this may be modified to any desired extent, and the direction of spraying and axis of an elongated 25 chamber may bear any desired relationship to the axis of the cylinder.

We also wish it to be clearly understood that we make no claim, per se, to the forms 30 of combustion chamber indicated, as we have already described such shapes of combustion chamber, for instance, in our applications for British Letters Patent No. 2974 of 1915 and 2976 of 1915.

35 This invention may be applied in either two-stroke or four-stroke cycle engines.

What we claim and desire to secure by Letters Patent is:—

1. In an internal combustion engine, the combination with a cylinder and a piston 40 reciprocable within said cylinder, of a combustion chamber oviform in longitudinal section and flattened at its sides, said combustion chamber being in communication intermediate the ends of its longitudinal axis 45 with the cylinder, whereby the center of the heat zone in the combustion chamber is disposed at one side of the longitudinal center of said chamber, and means at the smaller end of the combustion chamber for 50 injecting oil into said heat zone.

2. In an internal combustion engine, the combination of a cylinder, a piston reciprocable in said cylinder, a combustion chamber communicating with said cylinder, said 55 combustion chamber being transversely of oblate-spheroidal formation and of smaller diameter at one end than at the other, said combustion chamber communicating intermediate its length with the cylinder, and means at the smaller end of the said combustion chamber for injecting a spray of oil thereinto in the direction of its longitudinal axis.

In testimony whereof we have signed our 65 names to this specification in the presence of two subscribing witnesses.
